[57] CLAIM

The ornamental design for a telephone directory, as shown and described.

DESCRIPTION

FIG. 1 is a perspective view of a telephone directory, showing my new design;

FIG. 2 is a top plan view thereof;

FIG. 3 is a front elevational view thereof;

FIG. 4 is a rear elevational view thereof;

FIG. 5 is a bottom plan view; and

FIG. 6 is a right side elevational view, the left side being a mirror image thereof.

The broken line showing of an automobile sun visor in FIG. 1 is for illustrative purposes only and forms no part of the claimed design.

FIG. 1

FIG. 2

FIG. 4

FIG. 3

FIG. 5

FIG. 6
